UNITED STATES PATENT OFFICE.

AUGUSTUS H. HEISEY, OF PITTSBURG, PENNSYLVANIA.

GLASS VASE.

SPECIFICATION forming part of Letters Patent No. 354,416, dated December 14, 1886.

Application filed June 11, 1886. Serial No. 204,872. (No model.)

To all whom it may concern:

Be it known that I, AUGUSTUS H. HEISEY, residing at Pittsburgh, in the county of Allegheny and State of Pennsylvania, a citizen of the United States, have invented or discovered a certain new and useful Improvement in Glass Vases, of which improvement the following is a specification.

In the accompanying drawings, which make part of this specification, Figure 1 is a view in perspective of a glass vase embodying my invention, and Fig. 2 a vertical central section showing the same provided with a foot or base.

The object of my invention is to provide a vase adapted to serve as a convenient and ornamental receptacle for perfumery-bottles, toilet articles, flowers, &c., and which may be suspended or suited to rest upon a lower support, as desired.

To this end my invention, generally stated, consists in the combination of a conical glass body which is longitudinally swelled or corrugated and provided with a series of internal ledges or shoulders, and a central stem secured by a screw-thread and nut in the smaller end of the body; also, in the combination of a conical glass body, as above specified, a base or foot adjoining the smaller end thereof, and a central stem passing through the body and base, and provided with a clamping-nut by which it is secured thereto.

The improvement claimed is hereinafter more fully set forth.

In the practice of my invention I form a conical body, 1, of glass, which is pressed into a series of longitudinal swells or corrugations, 2, so as to be of a shape resembling a partially-opened parasol or umbrella. The outer surfaces of the swells 2 may be provided with any desired raised ornamentation—as, for example, what is known as a "hob-nail" pattern—for the whole or any desired portion of their length. A ledge or shoulder, 3, is formed on the inside of the pockets or recesses, which are provided by the swells or corrugations 2, said shoulders being located at any preferred distance below the top or larger end of the body 1, and serving as rests or supports for bottles deposited in the pockets. A central stem or handle, 4, which is preferably of metal and is provided with a ring or hook, 5, at its upper

end, is passed through a central opening in the smaller end of the body 1, and is secured thereto by a cap-nut, 6, engaging a screw-thread on the lower end of the stem 4, and 55 clamping a collar, 7, or a conical enlargement, 8, on the stem against a corresponding shoulder or tapering opening on the inside of the body.

In order to form a tight joint between the stem and body, so as to prevent leakage of 60 water when the vase is used as a receptacle for flowers, the hole in the body through which the stem passes is preferably made of conical or tapered form, and a corresponding tapered enlargement, 8, which fits therein, is formed 65 upon the stem.

The ring or hook 5 serves to suspend the vase from any suitable support, and the bottles or other articles placed in the pockets or recesses of the body are displayed clearly 70 through the glass. It will be seen that the vase also suitably serves as an ornamental receptacle for flowers or small toilet articles, and other adjuncts of a dressing-case or bureau.

In order to adapt the vase to stand upon a 75 table or other support, I provide a dished base or foot, 9, which may be either formed integral with the body 1, or, preferably, as shown, in a separate piece therefrom, the base in such case abutting against the smaller end of the 80 body, and being connected thereto by the stem 2, which passes through a central opening in the base, the cap-nut 6 being screwed to a bearing against the inside of the base. The base may be readily detached when it is desired to suspend the vase by the ring or hook 5. 85

I claim herein as my invention—

1. The combination of a conical glass body which is longitudinally swelled or corrugated, a central stem passing through and fitting 90 closely in an opening in the smaller end of the body and having a collar bearing against the inside thereof, and an external nut engaging a thread on the same, substantially as set forth.

2. The combination of a conical glass body 95 which is longitudinally swelled or corrugated, a series of ledges or shoulders located upon the inside of the swells of the body, and a central stem connected to the smaller end of the body, substantially as set forth. 100

3. The combination of a conical glass body which is longitudinally swelled or corrugated

and provided with a tapered or conical opening in the center of its smaller end, a stem having a conical enlargement fitting a corresponding opening in the smaller end of the body, 5 and a nut engaging a thread on the stem below said enlargement and bearing against the outside of the smaller end of the body, substantially as set forth.

4. The combination of a conical glass body 10 which is longitudinally swelled or corrugated, a base or foot abutting against the smaller end of the body, a stem passing through and

fitting closely in central openings in the body and base and having a collar bearing against the inside of the body, and a nut engaging a 15 stem and bearing against the lower surface of the base, substantially as set forth.

In testimony whereof I have hereunto set my hand.

AUGUSTUS H. HEISEY.
